UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed November 29, 1926. Serial No. 151,431.

My invention relates to rail anchoring devices for resisting the longitudinal movement of railroad rails.

The principal object of the invention is 5 to provide an improved rail anchor which may be made from a single piece of metal cut and bent to the desired configuration, which device, when applied to the base flange of a railroad rail will be distorted 10 so as to maintain its operative position on the rail by spring pressure, but which will take a positive hold on the rail to resist longitudinal creeping movement of the rail.

Another and more specific object is to 15 provide a one-piece anchor of the above general type in which the flexible portion of the anchor is relatively long so that the distortion of the anchor during its application to a rail will not produce a permanent set 20 in the flexible portion of the anchor.

The invention consists in the new and improved construction hereinafter described and claimed for carrying out the above 25 stated objects and such other objects of the invention as will appear from the detailed description of the embodiments shown in the accompanying drawings.

In the drawings:

Fig. 1 is a plan view of a railroad rail 30 showing one embodiment of my improved anchor device applied thereto in a position to bear against a cross tie.

Fig. 2 is a face view of the anchor device shown in Fig. 1 showing the same in a position which it assumes during the application 35 of the anchor to a rail.

Fig. 3 is another face view of the anchor device showing the same in its applied position.

Fig. 4 is a face view of the anchor device 40 showing the relative position of the jaw at one end of the anchor when the device is free of the rail.

Fig. 5 is a view similar to Fig. 1 showing 45 a modified embodiment of the invention applied to the base flange of the railroad rail.

Fig. 6 is a face view of the anchor showing 50 it in the position which it assumes when free of the rail and showing also the outline of the rail base in broken lines, and

Fig. 7 is a view of the metal blank from 55 which the embodiment shown in Figs. 5 and 6 is made.

Referring first to Figs. 1 to 4 inclusive 55 wherein I have shown one embodiment of the invention adapted to be driven transversely of the rail from one side thereof to its rail gripping position. This embodiment is made, preferably, from a flat strip of 60 spring metal, the upper edge of which is recessed to form a shoulder 10 at one end of the device and a jaw 11 at the other end. The end 12 of the metal strip is provided with a recess 13, which recess forms upper 65 and lower jaws 14 and 15. The end portion 12 of the anchor is bent to form a loop 16 so that the jaws 14 and 15 may be fitted over the edge of the rail base and grip the same adjacent the jaw 11 of the anchor. 70 The loop 16 is so formed, however, that the upper and lower jaws 14 and 15 are normally out of alignment with the jaw 11 and the upper edge 17 of the body, when the anchor is free of the rail. Preferably the jaw 14 75 extends below the lower edge of the jaw 11 and the upper edge of the jaw 15 extends downwardly and inwardly below the upper edge 17 of the body of the anchor so that it is necessary, in applying the anchor, to force the jaw 14 upwardly with relation to the upper edge 17 of the body. In applying the anchor to a rail, the body 18 is passed beneath a rail base and the jaws 11 and 14 are hooked over the upper edge 19 of the 80 rail base flange. In this initial position of the anchor, the shoulder 10 is beneath the rail base substantially as shown in Fig. 2. The end of the loop may be struck with a sledge or other suitable implement so as to 85 drive the anchor transversely of the rail until the shoulder 10 snaps up over the edge 20 of the rail base. During this transverse movement of the anchor, the jaw 14 is forced up on the inclined surface 21 of the rail 90 base so as to subject the loop 16 to a torsional stress and thereby move the jaws 14 and 15 from their oblique position into alignment respectively with the jaw 11 and the upper edge 17 of the body. The torsional 95 stress to which the loop is subjected exerts pressure upwardly against the bottom of the rail base adjacent the shoulder 10 of the anchor and also tends to tilt the jaw 11 and the upper edge 17 of the body about an axis 100 105

transversely of the rail so as to effect a shackle grip on the top and bottom surfaces of the rail base flange.

In Fig. 1 of the drawings I have shown the anchor positioned on the rail base so that the loop portion only bears against the vertical face of the cross tie 24. The position of the anchor may be reversed on the rail, however, so that the body will bear flatwise against the vertical face of the cross tie.

When the anchor is applied in the position shown in Fig. 1 of the drawings, any creeping movement of the rail toward the cross tie 24 tends to carry the shoulder end 10 of the anchor nearer the tie and thereby effects a positive shackle grip of the shoulder 10 and the vertical surface 25 of the jaw portion 14 on the opposite vertical faces of the base flange of the rail. When the anchor is applied in a reverse position so that the body bears flatwise against the vertical face of the cross tie, any tendency of the rail to creep toward the cross tie tends to rock the jaw 11 and the upper edge 17 of the body to effect a positive shackle grip on the top and bottom surfaces of the rail base.

In Figs. 5 to 7, inclusive, of the drawings, I have shown a modified embodiment in which the device is flexed transversely and vertically of the rail during its application. This modification is made from a blank 26 of the configuration shown in Fig. 7. The jaw 27 is bent at an angle to the body, preferably in a direction away from the cross tie, as shown in Fig. 5, and is formed so as to bear at the end 28 on the top surface 35 of the rail base. The vertical edge 29 at this end of the anchor bears against the vertical edge of the rail base. The other end of the blank is provided with a shoulder 30 adapted to engage the vertical edge 31 of the rail base. The extremity 32 of the blank is formed with a jaw 33 and the end is bent to form a resilient loop 34 so that the jaw 33 may be forced outwardly with respect to the edge of the rail base, to snap over the upper edge of said base. The extremity is so coiled that the lower surface 34 and the jaw 33 have to be flexed upwardly to engage the jaw 33 over the edge of the rail base flange.

In applying the modified embodiment to a rail, the jaw 27 is hooked over one edge of the rail base and the shoulder 30 is positioned adjacent the vertical face of the opposite edge of the rail base. In this position the end of the loop 34 may be forced outwardly with respect to the edge of the rail base and also forced upwardly so as to move the jaw 33 into engagement with the upper surface of the rail base. The outward and upward movement of this end of the anchor torsions the loop portion thereof so as to tend to tilt the extremity 28 of jaw 27 into spring gripping engagement with the top surface of the rail base.

The modified form of anchor is illustrated

in the drawings so that the loop portion bears against the vertical face of the cross tie. This type of anchor may, if desired, be reversed end for end in substantially the same manner as that suggested in connection with the form of anchor shown in Figs. 1 to 4 inclusive. When the anchor is applied in the position indicated in Fig. 5, any creeping movement of the rail in the direction toward the cross tie 24 tends to carry the angular jaw 27 nearer the cross tie and thereby effects a shackle grip of the shoulder 30 and the vertical portion 29 of the anchor on opposite edges of the rail base. The torsional stress to which the loop portion 34 is subjected holds the shoulder 30 up in its operative position so as to insure a positive shackle grip during the presence of any creeping pressure.

While I have illustrated my invention in two specific embodiments, it will be obvious that modifications in structure might be made without departure from the spirit of the invention. It will therefore be understood that I contemplate all changes in structure that come within the scope of the appended claims.

I claim:

1. A rail anchor comprising a body formed at one end with means for engaging the edge of the rail base at one side of the rail and provided at the other end with jaws adapted to be driven into gripping engagement with the rail base at the other side of the rail; said jaws being disposed out of alignment with each other whereby movement of said jaws to their operative positions distorts the anchor and exerts spring pressure upwardly at the other end of the anchor.

2. A rail anchor comprising a body formed at one end with a shoulder for engaging the edge of a rail base at one side of the rail and provided at the other end with jaws adapted to be driven into gripping engagement with the rail base at the other side of the rail; the said jaws being disposed out of alignment with each other whereby movement of said jaws to their operative position distorts the anchor and exerts spring pressure upwardly at the shoulder end of the said anchor.

3. A rail anchor comprising a body formed at one end with a shoulder for engaging the edge of a rail base at one side of a rail and provided at the other end with jaws adapted to be driven simultaneously into gripping engagement with the rail base at the other side of the rail; the said jaws being disposed out of alignment with each other, whereby movement of said jaws to their operative positions distorts the anchor and exerts spring pressure upwardly at the shoulder end of the anchor.

4. A rail anchor comprising a body formed

at one end with a shoulder for engaging the edge of a rail base at one side of a rail and provided at the other end with jaws adapted to be driven into gripping engagement with the rail base at the other side of the rail; the said jaws being disposed out of alignment with each other whereby movement of said jaws to their operative positions subjects the jaw end portion of the anchor to torsional stress and exerts spring pressure upwardly at the shoulder end of the anchor.

5. A rail anchor comprising a body formed at one end with a shoulder for engaging one edge of a rail base at one side of the rail and provided at the other end with jaws adapted to be driven into gripping engagement with the rail base at the other side of the rail; the said jaws being disposed out of alignment with each other so that movement of said 15 jaws to their operative positions subjects one end portion of the anchor to torsional stress, whereby one jaw and the upper edge of the anchor body are rocked longitudinally of the rail into shackle gripping engagement with the top and bottom surfaces of the rail base and whereby spring pressure is exerted upwardly at the shoulder end of the anchor.

6. A rail anchor comprising a bar provided at one end with a shoulder for engaging one edge of a rail base, at the other end with a jaw for engaging the other edge of the rail base and with a looped portion provided with a jaw which engages the rail base adjacent said first mentioned jaw; said jaws being normally disposed out of alignment with each other so that application of the 20 jaws to their operative positions moves them into alignment and subjects the loop portion to torsional stress.

40 7. A rail anchor comprising a bar provided at one end with a shoulder for engaging one edge of a rail base, at the other end with a jaw for engaging the other edge of the rail base and with a loop portion provided with a jaw which engages the rail base adjacent said first mentioned jaw; the said jaws being normally disposed out of alignment with each other so that application of the 45 jaws to their operative position moves them into alignment and subjects the loop portion to torsional stress, said loop portion being adapted to bear against the cross tie at one side of the rail whereby said shoulder and said first mentioned jaw take a shackle grip on opposite edges of the rail base during the presence of creeping pressure on the rail.

55 8. A rail anchor comprising a spring metal bar provided at one end with a shoulder for engagement with one edge of a rail base, at the other end with a jaw for engaging the other edge of the rail base and with a loop portion provided at its extremity with a jaw which engages the rail base adjacent said first mentioned jaw, the said jaws being normally disposed out of alignment with each

other so that application of the jaws to their operative positions subjects the loop portion to torsional stress.

9. A rail anchor comprising a spring metal bar adapted to extend across beneath a rail 70 base and formed at one end with means for engaging one edge of the rail base, at the other end with means for engaging the other edge of the rail base and with a loop portion adapted to bear against the cross tie at 75 one side of the rail and provided at its extremity with a jaw which engages the rail base adjacent the second mentioned rail engaging means and normally bears against said bar portion of the anchor; the arrangement of said jaw and loop being such that the loop is torsioned in applying said jaw to its operative position on the rail.

10. A rail anchor consisting of a spring metal member formed at one end with means 80 for engaging one edge of a rail base, at the other end with a jaw adapted to engage the top and vertical surfaces of the rail base, at the other side of the rail, and with a loop portion provided at its extremity with a jaw 85 adapted to engage said top and vertical surfaces of the rail base; said jaws being disposed so as to be applied simultaneously to their operative positions and whereby the anchor is subjected to torsional stress during 90 the application of said jaws to effect an initial shackle grip on the top and bottom surfaces of the rail base.

11. A rail anchor consisting of a spring metal member, relatively thin with respect 100 to its vertical dimension when applied to a rail and formed at one end with means for engaging one edge of a rail base, at the other end with a jaw adapted to engage the top and vertical surfaces of the rail base at one 105 side of the rail and with a loop portion provided at its extremity with a jaw adapted to engage the said top and vertical surfaces of the rail base; said jaws being so arranged that it is necessary to torsion said loop portion in moving the anchor transversely of the rail to its applied position, and whereby said means is snapped over the lower edge of the 110 rail base by the said torsional stress of the loop portion.

12. A rail anchor comprising a spring metal member formed at one end with means for engaging one edge of a rail base, at the other end with means for engaging the other edge of the rail base and with a 115 loop portion provided with a jaw which engages the rail base adjacent the second mentioned rail engaging means; the arrangement of said jaw and loop being such that the loop is torsioned and the jaw end of the 120 loop is flexed outwardly with respect to the adjacent edge of the rail base in applying the anchor to its rail gripping position.

13. A rail anchor comprising a flat metal body arranged edge-wise with respect to the 125

5 rail and one end of which is formed with
means for engaging a rail base flange at one
10 side of the rail and the other end of which
is bent upon itself and the bent over portion
15 formed with jaws adapted to be driven
transversely of the rail into gripping en-
gagement with the top and bottom surfaces
20 of the rail base flange at the other side of
the rail, the said jaw for bearing against
25 the bottom surface of the rail being disposed
normally oblique to the said bottom surface
during the initial position of the anchor on
30 the rail, whereby movement of the anchor
transversely of the rail to its applied posi-
35 tion exerts spring pressure upwardly at the
other side of the rail.

14. A rail anchor comprising a flat metal
body arranged edgewise with respect to the
20 rail and one end of which is formed with
means for engaging a rail base flange at one
25 side of the rail and the other end of which is
bent upon itself and the bent portion formed
30 with jaws adapted to be driven transversely
35 of the rail into gripping engagement with
the top and bottom surfaces of the rail base
40 flange at the other side of the rail, the said
jaw for bearing against the bottom surface
45 of the rail being disposed normally oblique
50 to the said bottom surface during the initial
position of the anchor on the rail, whereby
55 movement of the anchor transversely of the
60 rail to its applied position distorts said an-
65 chor adjacent said jaws and tends to tilt the
70 anchor body about an axis transversely of
the rail.

15. A rail anchor comprising a flat metal
body arranged edgewise with respect to the
20 rail, and one end of which is formed with
means for engaging the rail base flange at
25 one side of the rail and the other end of
which is bent upon itself and the bent over
30 portion formed with jaws adapted to be
35 driven transversely of the rail into gripping
engagement with the top and bottom sur-
40 faces of the rail base flange at the other side
45 of the rail, the said jaw for bearing against
50 the bottom surface of the rail being dis-
55 posed normally oblique to the said bottom
60 surface during the initial position of the
65 anchor on the rail, whereby movement of
70 the anchor transversely of the rail to its ap-
75 plied position distorts said anchor adjacent
80 said jaws and exerts spring pressure up-

wardly at the other side of the rail and
85 tends to tilt the anchor body about an axis
90 transversely of the rail to effect a shackle
95 grip on the top and bottom surfaces of the
100 rail base.

16. A rail anchor comprising a body, one
end of which is formed with means for en-
gaging a rail base flange at one side of the
15 rail and the other end of which is bent upon
itself and formed with a pair of upper and
20 lower jaws adapted to be driven into grip-
25 ping contact with the top and bottom sur-
30 faces of the rail base flange; said jaws being
35 normally out of alignment with respect to
40 each other when the device is free of the rail
45 and adapted to be moved into alignment by
50 movement of the anchor transversely of the
55 rail.

17. A rail anchor comprising a spring
60 metal body which is relatively thin with re-
spect to its vertical dimension when in its
65 applied position on a rail, formed at one end
70 with a shoulder for engaging one edge of a
75 rail base and provided at the other end with
80 jaws adapted to be driven into gripping en-
85 gagement with the opposite edge of said
90 base; the said jaws being disposed out of
95 alignment with each other so that movement
100 of said jaws to their operative position sub-
jects one end portion of the anchor to tor-
sional stress, whereby one jaw and the up-
105 per edge of the anchor body are rocked lon-
110 gitudinally of the rail into shackle gripping
115 engagement with the top and bottom sur-
120 faces of the rail base and whereby spring
125 pressure is exerted upwardly at the shoulder
130 end of the anchor.

18. A rail anchor comprising a flat plate
135 of spring metal arranged edge-wise with re-
spect to the bottom surface of the rail, pro-
140 vided at one end with a shoulder for engag-
145 ing one edge of a rail base, at the other end
150 with a jaw for engaging the other edge of
155 the rail base and with a looped portion pro-
160 vided with a jaw which engages the rail
165 base adjacent said first mentioned jaw; said
170 jaws being normally disposed out of align-
175 ment with each other so that application of
180 the jaws to their operative position moves
185 them into alignment and subjects the loop
190 portions to torsional stress.

HAROLD G. WARR.
